Term of patent 14 years

Int. Cl. D15—05

U.S. Cl. D7—167

FIG. 1

FIG. 2

FIG. 3

FIG. 4

FIG. 1 is a side elevational view of a carpet cleaner unit showing my new design;

FIG. 2 is a side elevational view thereof, as seen from the opposite side of FIG. 1, with the cord and hose omitted in part for ease of illustration;

FIG. 3 is a rear elevational view thereof; and

FIG. 4 is a front elevational view thereof.

The accordion-type hose pattern which is partially shown for ease of illustration is understood to repeat throughout the length of the hose in all views.

I claim:

The ornamental design for a carpet cleaner unit, substantially as shown and described.
